OIL BURNER

Charles R. Rau, Chattanooga, Tenn., assignor to
Samuel Stamping and Enameling Company,
Chattanooga, Tenn., a corporation of Tennessee

Application March 24, 1933, Serial No. 662,578

9 Claims. (Cl. 158—90)

This invention is an oil burner, of the type having a base provided with one or more oil grooves, and a combustion head comprising a plurality of cylindrical members perforated for the entrance of air. The combustion head is movable up and down with respect to the base so that the burner can be readily lighted. This general type of burner is well known, is in extensive household use today, usually burns with a blue flame and is oftentimes called a blue flame burner.

The present invention relates primarily to improved means for raising and lowering the combustion head. The means comprises a lever arrangement, designed for manual operation, which will raise the combustion head and automatically hold it in the raised position, and which will draw or pull the combustion head forcibly downwardly into tight engagement with the base.

It is of considerable importance in an oil burner that the combustion head be seated thoroughly and properly on the base. In the prior art, cam arrangements have been used for lifting the combustion head, but in these, the combustion head is lowered only by gravity. With the present invention, gravity is not relied on, mechanism being provided for forcibly pulling the combustion head to its seat and holding it there.

The preferred arrangement for accomplishing the raising and lowering of the combustion head comprises toggle lever mechanism which will be described more in detail. While an eccentric could be used for raising and lowering the combustion head and for forcibly pulling the combustion head into tight engagement with the base, a lever arrangement, specifically a toggle lever arrangement, is preferred.

Another important feature of the invention is that the combustion head, consisting of a plurality of concentric cylinders, is made as a unitary article which can readily be put in place or removed as a unit very quickly. This is particularly valuable in replacing, repairing or cleaning either the combustion head or the base.

Still another feature of the invention is that the oil groove or grooves in the base are provided with lugs for centering the starting wick and for holding it more or less vertical. With the ordinary oil groove the wick tends to bend, sag and get off center with respect to the groove.

More specifically, and in the preferred embodiment of the invention, there is provided a standard on which the base member carrying the oil grooves is mounted. On this standard there is

a vertically slideable sleeve provided with a shoulder near its upper end and the combustion head is provided with a rim which rests on this shoulder. The sleeve is threaded above the shoulder so that a wing nut will clamp the combustion head in place on the shoulder of the vertically slideable sleeve. There is a link pivoted at its upper end to the sleeve and pivoted at its lower end to a lever which is arranged to be manually turned about a horizontal axis. This link and lever arm forms a toggle.

The main features of the invention having been thus outlined, reference will now be made to the accompanying drawings illustrating the present preferred embodiment of the invention. It should be understood, however, that the disclosure is illustrative rather than restrictive of the invention, and may be carried out in other ways.

Referring now to the drawings in which similar reference characters indicate similar parts:

Fig. 1 is a perspective view of the improved burner;

Fig. 2 is a vertical section through the burner;

Fig. 3 is a section on the line 3—3 of Fig. 2 looking upwardly;

Fig. 4 is a side view partly broken away;

Fig. 5 is a horizontal cross section through Fig. 4;

Fig. 6 is a plan view in section of a portion of an oil groove; and

Fig. 7 is a section in elevation of an oil groove.

The burner comprises a suitable base 2, carrying a vertically disposed standard 4 of any suitable shape, but preferably rectangular in cross section. Secured to the standard by collar 6 is a base member 8, provided with a plurality of annular oil carrying grooves, here indicated as inner groove 10 and outer groove 12, suitable radial passages 14 being provided for the flow of oil between the inner and outer grooves, as is known in this art. Either or both of the oil grooves may be provided with a starting wick 15 and the walls of the grooves are or may be provided with a plurality of inwardly extending lugs 16, preferably arranged in oppositely disposed pairs, as shown more particularly in Figs. 6 and 7, for holding the wick in vertical position and preventing it from collapsing. Oil is fed into the grooves through an oil inlet pipe 17.

The several walls defining the oil grooves 10 and 12 are provided with seats 18, here shown as four in number, on which seats the lower edges of four concentric cylinders 20, 22, 24 and 26 are adapted to rest. These four cylin-

ders are perforated as is usual in this art for admitting air to the combustion spaces 28 and 30.

The four cylinders are suitably secured as by pins 32 to a top plate 34, this top plate being provided with four downwardly extending concentric rims 33, perforated for passage of the pins 32. The described cylinders and top plate form what is called a combustion head. The flame issues from slots 35 in the plate 34. The plate 34 is provided with a downwardly extending annular flange 36 which is adapted to seat on an annular shoulder 38 on the upper end of a sleeve 40, which sleeve surrounds and is 15 slidable on the standard 4. A washer 41 is secured in the sleeve 40, the washer having a rectangular opening for slidably fitting over the rectangular standard 4. The upper end of the sleeve is threaded as at 42 and the wing nut 44 is engageable with said threads and against plate 34, for clamping the combustion head in place against the shoulder 38 of the sleeve, and so it is clear that as the sleeve 40 is moved up and down, the combustion head is moved likewise. The combustion head is maintained in accurate alinement with the base member 8 and is held in a true vertical up and down path, by reason of the sleeve 40 being slidably positioned on the vertical standard 4, the sleeve acting as a bearing and guide. By virtue of this maintenance of alinement, the lower edges of the concentric cylinders 20, 22, 24, and 26 will always fit accurately onto their respective seats on the base member 8.

35 The mechanism for positively moving the combustion head up and down, which is one of the important features of this invention, will now be described. Such a mechanism comprises a link 46 which is pivoted at its upper end to a pin 48 attached to the sleeve 40; the link 46 is pivoted at its lower end by pin 50 to a lever arm 52 which is rigid with the horizontally disposed shaft 54, which shaft can be manually turned by the handle 56. Shaft 54 is mounted to turn in suitable bearings 58; these bearings may be integral with and part of the main or supporting collar 6. The link 46 passes through an opening 60 in the base member, the outer wall of the opening 60 being shown at 62.

50 It will be evident that when the shaft 54 is turned, the lever 52 will be raised, and link 46 will be raised so as to raise the sleeve 40 and the combustion head carried thereby. As the lever 52 reaches its upper position as indicated in dotted lines as in Fig. 4 it goes just past dead center, and one edge of the link 46 engages against wall 62 so that the link will hold the combustion head elevated. In order to lower the combustion head, the shaft 54 is turned in the opposite direction, which turns arm 52 downwardly, thereby exerting a downward pull on the link 46, which downward pull brings the lower edges of the perforated cylinders 20, 22, 24 and 26 into firm and tight engagement with their seats. If, due to warping, bending or other causes these cylinders tend to get out of line, the positive downward pull exerted by the links 46 will force the lower edges of the cylinders against their seats and hold them there. An accurate, tight and proper seating of the combustion head on the base is thereby always assured.

70 While the invention has been illustrated in considerable detail, it should be understood that the invention is not limited to the precise embodiment shown, but may be carried by other

mechanisms, as falling within the scope of the claims.

I claim as my invention:—

1. In an oil burner, in combination, a vertically positioned standard, a base member carried thereby, a sleeve slidably carried on said standard, the upper end of the sleeve being shouldered and threaded, a combustion head seated on the shoulder of the sleeve, a thumb screw engageable with the threaded part of the sleeve, for holding the combustion head in place on the sleeve, and toggle lever means, operatively connected to said sleeve, for raising the sleeve and combustion head, and for positively pulling the latter into engagement with the base member.

2. In an oil burner, in combination, a vertically positioned standard, a sleeve slidable on said standard, a base member, having oil carrying grooves therein, fixed with respect to the standard, a combustion head carried by the sleeve and vertically movable therewith, toward and away from said base member, the combustion head comprising a top plate and a series of concentric cylinders connected to the top plate, the lower edges of the cylinders being free, means engageable with the top of the sleeve and the top of the combustion head, for detachably securing them together, and means for moving the sleeve and the combustion head up and down on the standard.

3. In an oil burner, in combination, a vertically positioned standard, a sleeve slidable on said standard, a base member, having oil carrying grooves therein, fixed with respect to the standard, a combustion head carried by the sleeve and vertically movable therewith, toward and away from said base member, the combustion head comprising a top plate and a series of concentric cylinders detachably connected to the top plate, the lower edges of the cylinders being free, means engageable with the top of the sleeve and the top of the combustion head, for detachably securing them together, and means, including a shaft rotatable on a horizontal axis, operatively connected to said sleeve, for moving the sleeve and the combustion head up and down on the standard.

4. In an oil burner, in combination, a vertically positioned standard, a sleeve slidable thereon, a base member, having oil carrying grooves, fixed with respect to the standard, a combustion head carried by the sleeve, the combustion head comprising a top plate and a series of concentric cylinders detachably connected to the top plate, the lower edges of the cylinders being free, a link passing through the base member into operative engagement with said sleeve, and means for raising and lowering said link.

5. In an oil burner, in combination, a fixed standard, a base member having an oil channel therein adapted to hold a wick, said base member being mounted in fixed relation to said fixed standard, a sleeve member slidably mounted on said fixed standard in snugly fitting engagement therewith, a combustion head comprising a top portion and a plurality of perforated cylinders adapted to fit in registering engagement with said base member, said top portion being connected to said sleeve member adjacent the upper portion of the sleeve member, the sleeve member being substantially entirely within the combustion head manually operative means for moving said sleeve member on said

standard so as to bring said cylinders into and out of engagement with the base member and stop means for holding the said combustion head in raised position to permit access to said 5 burner base.

6. In an oil burner, in combination, a fixed standard, a base member mounted on said standard, said base member having an oil channel therein adapted to hold a wick, a sleeve member 10 slidably mounted on said standard in snugly fitting engagement therewith, a combustion head carried at the upper part of said sleeve member, said combustion head having a top portion and a plurality of perforated cylinders adapted to 15 engage said base member, connecting means for removably holding the combustion head on said sleeve member, with the sleeve member positioned substantially entirely within the combustion head said connecting means being positioned above said top portion so as to be readily 20 accessible for disconnecting said combustion head from the sleeve member, and means for raising and lowering the sleeve member to permit access to said base member.

7. An oil burner comprising a stationary base member having concentric oil channels therein, each of said channels being adapted to hold a burner wick, means providing communication between said channels, means for feeding oil to 30 one of said channels, a supporting standard mounted in fixed relation to said base member, a sleeve member slidably mounted on said standard, a combustion head having a top plate and a plurality of perforated concentric cylinders 35 carried by said top plate forming walls adapted to engage said oil channels when the said combustion head is in position on said base member, connecting means for removably holding the said combustion head on the upper portion of 40 said sleeve member, said connecting means comprising a screw threaded nut carried by the said sleeve member positioned above the said top plate so as to be readily accessible for disconnecting the combustion head from the said 45 sleeve member, the sleeve member being positioned substantially entirely within the combustion head a series of openings through said

burner top communicating with the spaces between said concentric cylinders to emit combustion gases during operation of the burner, lever means including a link member connected to 5 said sleeve for raising said sleeve so as to positively move the said combustion head upwardly from the burner base and to cause positive seating engagement of the said cylinders on the said base member and stop means for holding the said combustion head in raised position. 10

8. In an oil burner, in combination, a combustion head comprising a centrally apertured top plate and a plurality of perforated concentric cylinders carried by the underside of the top plate and depending therefrom, a vertically 15 positioned, fixed standard of a length sufficient to project through the central aperture in the top plate, a sleeve, slideable on the standard, within the combustion head, and projecting through the aperture in the top plate, manually 20 operated means, engageable with the top plate and with the upper portion of the sleeve and positioned above said top plate so as to be freely accessible, for detachably securing the top plate and the sleeve together, and means 25 for raising and lowering said sleeve.

9. In an oil burner, in combination, a combustion head comprising a centrally apertured top plate and a plurality of perforated concentric cylinders carried by the underside of the 30 top plate and depending therefrom, a vertically positioned, fixed standard of a length sufficient to project through the central aperture in the top plate, a sleeve, slideable on the standard, within the combustion head, and projecting 35 through the aperture in the top plate, manually operated means, engageable with the top plate and with the upper portion of the sleeve and positioned above said top plate so as to be freely accessible, for detachably securing the top plate 40 and the sleeve together, and manually operated means, comprising a shaft turnable on a horizontal axis, connected to said sleeve by link means, for positively raising and lowering said sleeve, and the combustion head connected 45 thereto.

CHARLES R. RAU.
